ROLF GUNNAR CERVIN, OF STOCKHOLM, AND BIRGER SILFVERLING, OF ARBOGA,
SWEDEN.

SIDE SCUTTLE.

1,303,537.

Specification of Letters Patent.

Patented May 13, 1919.

Application filed June 4, 1917. Serial No. 172,747.

To all whom it may concern:

Be it known that we, ROLF GUNNAR CERVIN and BIRGER SILFVERLING, subjects of the King of Sweden, residing at 137 Ringvägen, 5 Stockholm, Sweden, and Arboga, Sweden, have invented new and useful Improvements in Side Scuttles, of which the following is a specification.

The present invention has for its object 10 improvements in side-scuttles.

Such scuttles, hitherto known, consist of a window hinged in a frame firmly connected to the outside plating, the space between this frame and the inner wall being usually 15 filled up with wood in such a manner that a funnel shaped aperture is formed.

As experience has shown, this arrangement, however, is not at all satisfactory, because the water and the moisture from the 20 scuttles without difficulty make their way between the outside plating and the wall, thus causing the corrosion of the former below the scuttles, making it necessary often to inspect this part of the outside plating.

25 The present invention now has for its purpose to avoid this inconvenience and consists essentially in providing the frame with or connecting it watertightly to an endless flange or collar, extending from the scuttle 30 frame to the wall, to which it conveniently is connected. This flange prevents the water, entering through the scuttle or condensed upon the window glass, from making its way between the outside plating and the 35 wall, and the flange causes said water or condensate to flow to the inner side of the wall where it can be collected in any usual manner. For obtaining a tight and easily 40 executed connection between the flange and the wall, the flange according to one form of the invention is provided at its inner end with a shoulder forming a support for the wall.

45 This shoulder of course may be constructed in different ways depending upon the kind of the wall used and the appearance required.

The invention is illustrated in the accompanying drawing. Figure 1 illustrates the 50 side-scuttle and the adjacent parts of the vessel in side view and partial vertical section and Fig. 2 the same scuttle seen from the inside. Fig. 3 illustrates a somewhat modified construction of the shoulder of the 55 scuttle flange.

In Figs. 1, 2 1 is a scuttle-frame which usually is riveted to the outside plating 2, and 3 is the window-sash hinged to the frame 1 for permitting the opening of the window. 4 is the usual locking-means for 60 the window and 5 is a dead door arranged inside the latter. The window-sash is held tightly against the frame 1 by means of a packing 6 of rubber or the like, and a similar packing 7 is arranged between the dead 65 door 5 and the window-sash 3.

According to the present invention the frame 1 is united or made in one piece with a flange 8, extending from the frame 1 to the wall 9 and being suitably of an annular, 70 conical shape, thus preventing the water from the window from making its way between the outside plating 2 and the wall 9. Hereby the inconvenience above stated is removed. According to the invention the 75 flange 8 at its inner end may be provided with a shoulder 10, by means of which the wall can easily be connected to the flange 8.

For obtaining a perfectly water-tight and 80 firm connection between the wall and the flange 8 the shoulder 10 can be provided with an annular groove 11, in which the wall is introduced; such a modification is 85 illustrated in Fig. 3.

It is, however, not necessary that the flange 8 be provided with such a shoulder, and if used it does evidently not need to be arranged at the end of the flange.

In the drawings the invention is illustrated in connection with a window which can be opened, but it is evident, that the invention has the same advantages with scuttles which cannot be opened, because in them moisture will be collected and cause the inconvenience already mentioned. Furthermore the flange 8 is shown of a conical shape, but this form of course is not necessary because the advantage of the invention also is obtained if the flange for instance should be of a cylindrical or square shape.

In the building of new vessels the scuttle-frames conveniently will be cast in one piece with the flange but in rebuildings it may for 105 economical reasons be advantageous to use a loose flange, which is brought in watertight connection with the frame for instance by packings and screws or the like.

Having now particularly described the 110

nature of our invention and the manner of its operation, what we claim is:

1. The combination with the side of a ship having a space between the outer plating and inner wall, of a scuttle frame fixed to the outer plating and provided with a continuous flange which extends from the frame across the space to the inner wall, said flange having a smooth inner surface for guiding moisture to the inner side of the inner wall.
2. The combination with the side of a ship having a space between the outer plating and inner wall, of a scuttle frame secured to the outer plating and provided with a continuous flange which extends across the space to the inner wall and has a flaring mouth opening inwardly, for guiding moisture through the space.
3. The combination with the side of a ship having a space between the outer plating and inner wall, of a scuttle frame secured to the outer plating and provided with a conical flange which extends across the space and has its larger end connected to the wall for guiding moisture across the space and preventing leakage into the space.
4. The combination with the side of a ship having a space between the outer plating and inner wall of a scuttle frame secured to the outer wall and carrying a scuttle closure and a continuous flange carried by the

frame, extending across the space and provided at its inner end with a shoulder for connecting the same to the inner wall.

5. The combination with the side of a ship having a space between the outer plating and inner wall of a scuttle frame secured to the outer wall and carrying a scuttle closure and a continuous flange carried by the frame, extending across the space and provided at its inner end with a shoulder for connecting the same to the inner wall, said shoulder being provided with a recess for the reception of the wall.

6. The combination with the side of a ship having a space between the outer plating and inner wall, of a scuttle frame secured to the outer plating and provided with an inwardly extending flared flange for conveying moisture from the frame toward the inner side of the wall, a scuttle closure carried by the frame, and a recessed shoulder integral with the inner end of the flange for securing the flange to the wall.

In testimony whereof we have signed our names to this specification in the presence of two subscribing witnesses.

ROLF GUNNAR CERVIN.
BIRGER SILFVERLING.
